UNITED STATES PATENT OFFICE.

SAMUEL B. ROBERTSON, OF AKRON, OHIO, ASSIGNOR TO THE B. F. GOODRICH COMPANY,
OF NEW YORK, N. Y., A CORPORATION OF NEW YORK.

DESIGN FOR A PNEUMATIC TIRE.

Application filed December 28, 1923. Serial No. 8,176. Term of patent 14 years.

To all whom it may concern:

Be it known that I, SAMUEL B. ROBERTSON, a citizen of the United States, residing at Akron, in the county of Summit and State of Ohio, have invented a new, original, and ornamental Design for a Pneumatic Tire, of which the following is a specification, reference being had to the accompanying drawing, forming a part thereof.

Fig. 1 is a fragmentary plan view of a pneumatic tire casing showing my design.

Fig. 2 is a fragmentary side elevation of the same.

Fig. 3 is a cross section on the line 3—3 of Fig. 1, omitting internal structural details.

I claim:

The ornamental design for a pneumatic tire as shown.

SAMUEL B. ROBERTSON.
